GRINDING MACHINE

George F. Maglott, Wrentham, Mass., assignor
to Brown and Sharpe Manufacturing Company,
a corporation of Rhode Island

Application March 3, 1936, Serial No. 66,803

20 Claims. (Cl. 51—233)

The present invention relates to grinding machines and is herein disclosed as embodied in a hydraulically driven surface grinding machine having a rotary grinding wheel, a reciprocable work table, and a cross slide on which one of said parts is carried.

It is a primary object of the invention to provide in a machine of this description, a novel and improved hydraulic operating and control mechanism which is of simple construction and is well adapted to insure a maximum degree of versatility and accuracy in the operation of the machine.

It is more specifically one object of the invention to provide a novel and improved hydraulic cross feed mechanism for the machine which is well adapted for intermittent operation to impart closely regulated increments of relative transverse movement to the grinding wheel and work in timed relation to the table reciprocation for the grinding of successive portions of a flat work piece.

With these and other objects in view as may hereinafter appear, a principal feature of the invention consists in the provision of a metering valve arranged to supply measured amounts of liquid to the cross feed cylinder and ram of the machine, for imparting accurately determined increments of cross feeding movement in timed relation to the lengthwise reciprocation of the work with relation to the grinding wheel.

Another feature of the invention consists in the provision in the exhaust line from the cross feed cylinder and ram, of a check valve which is arranged to provide a relatively high back pressure against the operation of the metering valve, and so to insure the accurate operation of the hydraulic cross feed devices to produce the desired relative movement of the work and grinding wheel, and to maintain these elements firmly in their adjusted position.

In accordance with another feature of the invention, a control mechanism is provided for the cross feed which comprises a cross feed reversing and shut-off or hand feed valve having alternative operating positions in which the cross feed will operate in opposite directions, and a third hand position in which the supply of liquid under pressure is shut off, and a by-pass is provided directly from one end to the other of the cylinder to facilitate a manual operation of the cross feed.

Another feature of the invention consists in the provision of an interlock between the table throttle valve and the cross feed truing controls for the machine which is rendered operative dur-

ing table reciprocation or alternatively during wheel truing, to lock the other of said controls out of operation.

The several features of the invention consist also in the devices, combinations and arrangement of parts hereinafter described, which together with the advantages to be obtained thereby, will be readily understood by one skilled in the art from the following description taken in connection with the accompanying drawings, in which Fig. 1 is a view in right side elevation partly in section, of a surface grinding machine embodying in a preferred form the several features of the invention; Fig. 2 is an enlarged detail view in front elevation of the control panel of the machine as indicated by the line 2—2 of Fig. 1; Fig. 3 is a sectional view taken on the line 3—3 of Fig. 2; Fig. 4 is an enlarged plan view partly in section, of the several control valves taken substantially on the line 4—4 of Fig. 2; Fig. 5 is a detail sectional view of the truing valve taken on the line 5—5 of Fig. 2; Fig. 6 is a detail front view partly in section, of the table and saddle; Fig. 7 is an enlarged detail sectional view of the saddle dog control mechanism as shown in Fig. 6; Fig. 8 is an enlarged detail sectional view of the manual cross feed mechanism as shown in Fig. 6; Fig. 9 is an enlarged sectional detail view of the right hand end of the table cylinder as shown in Fig. 6; Fig. 10 is a plan sectional view taken on the line 10—10 of Fig. 2; Fig. 11 is a detail sectional view taken on the line 11—11 of Fig. 10; Fig. 12 is a sectional view taken on the line 12—12 of Fig. 2; and Fig. 13 is a diagrammatic view of the hydraulic operating connections for the machine.

The machine illustrated in the drawings comprises a base 20, a vertically adjustable column 22 on which is carried a grinding wheel 24 and a rotary spindle 26, a reciprocable work table 28, and a transversely movable saddle support 30 for the table.

The grinding wheel spindle 26 as best shown in Fig. 1, is preferably driven from an electric motor 32 mounted in the lower part of the column 22 through connections which include a pulley 34 on the spindle 26, a pulley 36 on the armature shaft of the motor 32, and a belt 38 as shown in dotted lines Fig. 1. Vertical adjustment of the column 22 is effected through connections generally indicated in dotted lines in Fig. 1, which include a cooperating screw 40 and nut 42 supported respectively on the column 22 and base 20, a hand wheel 44, shaft 46, a bevel gear 48, and a ring gear 50 secured respectively to the shaft 46 and to the upper end of the screw 40.

The table 28 of the present machine is mounted to slide on ways 62 and 64 (see Figs. 1 and 6) formed on the saddle 30 and is driven through hydraulically operated connections which include 5 a cylinder 55 rigidly secured to the saddle 30, and a piston 56 which is connected to move with the table 28 by means of a piston rod 58 passing through a packing box 59 in the cylinder, and secured at its outer end to a bracket 60 on the 10 under side of the table.

The saddle 30 is mounted for movement transversely of the direction of table movement on two V-shaped ways 62 and 64 on the base 20, and is arranged for manual operation by means of a 15 hand wheel 66 and screw 68 supported on the saddle 30 for engagement with a split nut 70 carried on the base 20, as hereinafter more fully described, or for power operation by hydraulically operated connections including a cylinder 72 20 (Figs. 1 and 13) secured to the under side of the saddle 30 and a piston 74 which is supported in a stationary position by means of a piston rod 75 passing through a packing box 76 in the cylinder and secured at its outer end to a lug 78 on the 25 base 20.

Oil under pressure is supplied to the cylinder 55 to control the direction and rate of travel of the table 28 through connections which include a 30 table throttle valve 80 and a table reversing valve 82 comprising a valve casing and an axially movable valve member 86. In order to insure an accurate and positive operation of the table reversing mechanism, there is also provided with the present construction, a table reversing pilot 35 valve 84 which may be actuated either manually or automatically by means of table dogs, and operates hydraulically to shift the table reversing valve member 86 as hereinafter more fully to be described.

40 Oil under pressure is drawn from an oil reservoir 88 in the base of the machine (see Fig. 13) by means of an oil pump 90 which may be of any ordinary description, passing through a pipe 92 to the throttle valve 80. The throttle valve 80 preferably comprises a rotatable cylindrical member 94 having formed in the wall thereof an irregular slot or aperture 96 which may be moved into or out of register with an outlet pipe 98 to the reversing valve 82. The angular position of 45 the throttle valve cylinder 94 is controlled to determine the rate of flow of liquid through the valve and the corresponding rate of table travel by means of a rotatable valve stem 100 secured to the member 94 and provided at its forward end 50 with a manually operable control knob 102.

55 Liquid under pressure passes from the throttle valve 80 through the pipe 98 into a chamber 104 formed by a reduced or spool portion of the reversing valve member 86, and thence through 60 either of two pipes 106 and 108 depending upon the position of the reversing valve member 86 to one end or the other of the table driving cylinder 55 and piston 56. Liquid is allowed to pass from the exhaust end of the table cylinder 55 65 through the pipe 108, a chamber 110 formed by a reduced or spool portion of the reversing valve member 86 and pipe 112 forming the exhaust line to the reservoir 88, or alternatively through the pipe 106, a chamber 114 in the reversing valve, 70 and an extension of the exhaust pipe 112 to the reservoir.

In the preferred construction illustrated, a shock absorber device is provided to cushion the stopping of the table, when the piston 56 is permitted to travel to the extreme end of the cylinder.

der 55 as when the table reversing valve 82 is set for operation in one direction, and is not thereafter reversed either manually or automatically as hereinafter described. As best shown in Fig. 6 of the drawings, the entering 5 ports 107 and 109 to the table cylinder 55 from the pipe connections 106 and 108 are located at a slight distance from the adjacent end walls of the cylinder 55. There is also provided at the left hand end of the cylinder an additional port 10 111 to the pipe connection 106 in the form of a narrow slot which extends longitudinally to the extreme end of the cylinder. Similarly, there is provided at the right hand end of the cylinder 55, a port 113 to the pipe connection 108 in the 15 form of a narrow slot which extends longitudinally to the adjacent end of the cylinder. With this construction and arrangement of the ports 107, 109, 111 and 113, it will readily be seen that as the piston 56 approaches, for example, the left 20 hand end of the cylinder 55, the port 107 will be shut off allowing only a very restricted exhaust of the remaining oil in this end of the cylinder through the port 111. As the piston 56 continues its movement to the left, the port 111 is gradually 25 closed so that a continuously increasing back pressure to the continued movement of the piston 56 is built up to correspondingly check the speed of the table 28 and piston 56 which are thus brought gradually to a stop without shock or jar. 30

In order to maintain the pressure in the system at a substantially constant predetermined level, there is provided in the supply line 92 from the pump 90, a high pressure relief valve generally indicated at 116 which for purposes of illustration may be assumed to have a setting of 100 lbs. per square inch. A similar relief valve generally indicated at 118 is provided in the exhaust line 112 which may be assumed to have a setting of 4 lbs. per square inch, so that a sufficient back pressure is maintained at all times 40 to prevent ingress of air in the system.

In accordance with one feature of the invention, a master stop valve is provided for the machine which operates to connect the pressure line 92 directly to the exhaust line 112, so that all 45 of the hydraulically controlled portions of the machine are rendered inoperative, and further operates to provide a by-pass from one end of the table cylinder 55 and ram 56 to the other independently of the position of the table reversing valve member 86. The master stop valve comprises a cylindrical valve member 120 having formed therein two transversely extending ducts 122 and 124 which for one angular position of the member 120 form connecting passageways respectively in the pipe lines 106 and 108 to the table cylinder 55. There is also formed in the valve member 120, a longitudinally extending duct 126 which is arranged for another or stop position of the valve member 120 to provide a direct connection between the lines 106 and 108 leading to the table cylinder 55, and also for this position of the valve connects an extension 128 50 of the supply line 92 directly to an extension 130 of the exhaust line 112. With the stop valve member 120 in the operating position shown in Fig. 13, the extensions 128 and 130 respectively of the supply and exhaust lines are shut off, and liquid is permitted to flow freely between the 55 reversing valve 82 and the table cylinder 55 through pipes 106, 108 and ducts 122 and 124. When the stop valve member 120 is turned to stop 60 position, the connecting portions of the pipes 106 and 108 from the reversing valve are shut off, 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

and pipes 106, 108 and extensions 128 and 130 of the supply and exhaust lines are directly connected by the duct 126, so that the two ends of the cylinder 55 are connected to each other to prevent locking of cylinder and piston, and also to supply and exhaust to insure the maintenance of a full supply of oil in the system during manual operation.

The position of the master valve member 120 is controlled through connections which include, a pinion 134 (see Figs. 6, 7, 10 and 11) formed on one end of the valve member 120 which meshes with a rack 136 on an axially movable control rod 138. A compression spring 140 coiled about the rod 138 between an abutting portion of the rack 136 and a stationary collar 142 secured by a screw 143 to the saddle, tends normally to move the rod rearwardly to maintain the valve member 120 in stop position. In accordance with one feature of the invention, a latch mechanism for holding the control rod 138 in a forward or operating position is provided which may be tripped automatically through the operation of dogs on the saddle 30 or manually by a light pressure on the part of the operator to cause the control rod 138 and valve member 120 to move to stop position under the pressure of the spring 140. The latch comprises a laterally extending arm 144 secured to a rock shaft 146 and arranged for engagement with a notch 148 in the control rod 138 to maintain the valve in operating position. Also secured to the rock shaft 146 is an upwardly extending lever arm 150 which contacts with one end of a pin or plunger 152 supported in a bore 154 which extends laterally through the saddle casting directly above the saddle way 64. A compression spring 156 seated at one end in a recess in the lever 150 and at its other end in a recess in the saddle casting, tends to rock the lever 150, shaft 146 and latch 144 in a direction to engage the latch in its notch 148 and to maintain the arm 150 and pin 152 in a fully extended position. The latch 144 may be tripped automatically to stop the machine by the movement of the saddle 30 to a predetermined position in either direction by means of dogs 158 adjustably mounted in a T-shaped slot 160 in the base 20, which are arranged to contact with and move the pin 152 and lever arm 150 to the right (see Figs. 6 and 7) against the pressure of the spring 156 to release the latch 144.

For manual operation of the control rod 138, there is provided on the forward end thereof, a cylindrical cap 162 which is connected for a limited axial movement on the shaft 138 by means of a pin 164 secured to the shaft and extending through a longitudinal slot 166 in the cap 162. As best shown in Fig. 11, one side of the cap 162 is cut away to form a cam surface 170 which is arranged when the cap 162 is pushed inwardly by the operator, to engage against and trip the latch 144 to stop the machine.

In order to enable the operator readily to move the control rod 138 and master valve member 120 to running position against the pressure of the spring 140, a manually operable lever 172 is pivotally supported on a rod 174 on the front of the machine, and is provided with a slotted portion 175 to receive a forward extension of the cap 162 which is provided at its outer end with an enlarged head 176, so that a forward movement of the hand lever 172 will operate to move the cap 162 and control rod 138 connected thereto forwardly to running position. A spring 178 coiled about the pivot rod 174 between the two

arms of the forked hub of the lever 172, and connected at one end to the lever, tends to maintain the hand lever 172 in a fully retracted inoperative position (see Figs. 2 and 10).

For the manual operation of the table 28, a table hand wheel 171 is rigidly secured to the forward end of a shaft 173 (see Figs. 1, 10 and 13) which is supported for rotational and limited axial movements in bearings formed in the saddle 30. A pinion 177 secured to the rear end of the shaft 173 is arranged for a relatively advanced position of the shaft 173 and hand wheel 171 to mesh with a rack 179 secured to the table 28. A spring-pressed plunger 181 supported in an adjacent portion of the saddle is arranged for engagement alternatively with one of two grooves formed in the shaft 173 to maintain the shaft 171 and pinion 177 alternatively in an advanced operative or retracted inoperative position.

In accordance with the present invention, hydraulically operated connections are provided which are rendered operative upon movement of the master control valve 120 of the machine to operative position, to force the hand wheel shaft 173 rearwardly to disconnect the pinion 177 from the rack 179, and to permit a forward movement of the shaft 173 to operatively connect the table hand feed only when the master valve 120 is turned to stop position. The connections provided to this end, comprise a piston 183 secured to the hand wheel shaft 173 and arranged for axial movement in a cylinder 185 through which the shaft 173 extends. Oil under pressure is supplied to the cylinder 185 by means of an extension 189 of the supply line 92, and operates during the normal operation of the machine to force the piston 183 and hand wheel shaft 173 secured thereto rearwardly to inoperative position. When the master valve 120 is turned to a stop position, exhausting the relatively high driving pressure in the hydraulic system of the machine as above described, the hand wheel 171 and shaft 173 may be moved forwardly to engage the pinion 177 with the rack 179 with relatively little effort on the part of the operator, being maintained in this position by the action of the spring plunger 181 in its cooperating groove as above described.

The table reversing pilot valve 84 through which the operation of the table reversing valve member 86 is preferably controlled, comprises an axially movable valve member 180 which is controlled through mechanical connections including a control lever which may be operated either manually or automatically by engagement with dogs adjustably supported on the table. The pilot valve member 180 is connected by means of a rod 182 to a lever arm 184 on a vertically extending post 187 on the saddle 30 which has secured at its upper end an actuating lever 188. The lever 188 is formed for convenient manipulation by the operator, and is further provided with a rearward extension for engagement with table dogs 190 adjustably supported in a T-shaped slot 192 formed in the table.

The operation of the pilot valve to control the position of the table reversing valve member 86 will be readily understood from an inspection of the partly diagrammatic Fig. 13 of the drawings. Liquid under pressure passes from the supply line 92 through a pipe connection 194, and a throttle valve 196 which may be of ordinary construction, to a chamber 198 formed by a spool portion of the pilot valve member 180, and thence through pipe connection 200 or 202 to one end or the other of the reversing valve 82 depend-

ing upon the position of the pilot valve member 180. Simultaneously liquid is exhausted from the opposite end of the reversing valve 82 through the other of said connections 200 and 202 through 5 one of two chambers 204 and 206 formed by spool portions of the pilot valve member 180 and exhaust connections therefrom hereinafter more fully to be described. With the construction and mode of operation of the table reversing valve 82 10 and pilot valve 84 associated therewith as above described, in which the position of the table reversing valve member 86 is shifted through the operation of hydraulically operating means, it will readily be seen that a certain and accurate 15 operation of the table reversing mechanism is secured to insure a uniform operation of the reversing valve and to avoid any possibility of stalling the table upon reversal.

In accordance with the present invention, a 20 novel and improved hydraulic mechanism is provided for imparting cross feeding movements to the saddle 30 in timed relation to the longitudinal reciprocatory movements of the table which comprises a metering valve generally indicated at 25 210 adapted for supplying measured amounts of liquid under pressure to one end or the other of the cross feed cylinder 72 and ram 74 to advance the saddle by steps of predetermined length. The metering valve 210 comprises a cylindrical casing within which a piston 212 is free to move back and forth, the length of movement being regulated by means of an adjusting screw 214 threaded into one end of the cylinder 210 to serve as a stop for the piston 212 and provided at its outer end with a knurled head 216 30 for adjustment by the operator. In the operation of the device, liquid under pressure is admitted into one end of the metering valve 210 driving the piston to the opposite end of the cylinder and forcing the liquid contained therein through connections hereinafter described, into one end or the other of the cross feed cylinder 72 to cause a relative displacement of the ram 74 in the cross feed cylinder 72 which will correspond exactly to the volume of liquid expelled 35 from the metering valve 210.

Further in accordance with the present invention, the operation of the metering valve 210 is controlled by means of a cross feed control valve 220 having a movable valve member 222 which is in turn controlled by the operation of the reversing valve member 86 above described, to cause the intermittent cross feeding movements to take place automatically at the end of 50 the table movement in each direction. The cross feed control valve member 222 has formed thereon two reduced or spool portions to form chambers 224 and 226 within the valve and in the ends thereof cylindrical bores 228 and 230 which are arranged to fit over cylindrical plugs 232 and 234 respectively, formed in opposite ends of the valve cylinder 220.

The control valve member 222 is shifted in one direction or the other between two extreme positions at opposite ends of the valve cylinder 220 55 at each reversal in the position of the pilot valve member 180 and table reversing valve member 86 to reverse the direction of table travel by means of the exhaust pressure set-up in one of the pipe connections 200 or 202, by the movement of the reversing valve member 86 from one to the other of its alternative operating positions. This exhaust pressure passes from the connection 200 and chamber 204 in the pilot 60 valve 84 through a connection 236 including an

axial bore in the plug 232 to the left hand end of the control valve (see Fig. 13), or alternatively from connection 202 and chamber 206 in the pilot valve 84 through a connection 238 including an axial bore in the plug 234 to the right 5 hand end of the control valve 220. In order to take care of excess liquid exhausted from the ends of the reversing valve 82, through connections 200 or 202 to the control valve 220 as above described, two extensions 240 and 242 of the exhaust line 112 are connected to each end of the control cylinder 220 so that as the valve member 222 moves to its extreme position in which the plug 232 or 234 is disengaged from the corresponding bore in the control valve member 222, 10 additional liquid exhausted from the reversing valve as above described, is permitted to flow freely past the plug 232 or 234 as the case may be, to the corresponding extension 240 or 242 of the exhaust line 112. Liquid is exhausted from 15 the leading end of the control cylinder 220 as the valve member 222 is moved from one extreme position to the other through the connection 236, chamber 204 in the pilot valve 84 and an exhaust connection 244 therefrom, or alternatively 20 through the connection 238, chamber 206 in the pilot valve 84 and an exhaust connection 246.

The operation of the control valve 220 and metering valve 210 to impart a step-by-step feeding movement to the saddle 30 may be described as follows: Assuming that the control valve member 222 has been moved to the right to the position shown in Fig. 13, liquid under pressure passes through an extension 250 of the supply line 92 and a throttle valve 252 which may 25 be of ordinary construction, into the chamber 224 of the control valve 220, and thence through a connection 254 to the left hand end of the metering valve 210, causing the piston 212 to be forced to its extreme position to the right as 30 shown in Fig. 13. The liquid thus expelled from the right hand end of the metering valve 210 passes through a connection 256 into the chamber 226 in the control valve 220, and thence through an outlet 258 to a cross feed reversing 35 and shut-off valve 260 from which the liquid passes through one of two connecting pipes 262 and 264 to the left hand or right hand end of the cross feed cylinder 72 depending upon the setting of the valve 260 to impart the desired increment of movement to the saddle 30.

Upon movement of the control valve member 222 to the left from the position shown in Fig. 13 upon the next reversal in the position of the table reversing valve member 86, the connection 258 is 40 shut off, and the throttle valve 252 is connected to the chamber 226 and connection 256, thus causing liquid under pressure to be forced into the right hand end of the metering valve 210 to move the metering valve member 212 to the left. 45 At the same time the connection 254 to the left hand end of the metering valve 210 is shut off from the supply line including the throttle valve 252, and is then connected through the chamber 224 and a connecting pipe 266 to the cross feed 50 reversing and shut-off valve 260 so that the liquid forced out of the left hand end of the metering valve will pass through these connections to impart an additional increment of movement to the saddle 30 measured by the volume of liquid 55 in the metering valve.

The cross feed reversing and shut-off valve 260 as best shown in Figs. 12 and 13, comprises a casing through which extends a tapered rotatable valve member 268 having cut in opposite sides 70

thereof two ducts 278 and 272. The valve member 268 may be turned to any one of three positions including an "in" feed position shown in full lines in the diagrammatic Fig. 13, which illustrates a sectional view of the valve looking from the rear, the shut-off, or hand feed position indicated at 274 in dotted lines, and an "out" feed position similarly indicated at 276. In the full line position of the valve member 268 illustrated, liquid flows from the metering valve 210 as above described, through the port 270 and connection 262 to the rearward or left hand end of the cross feed cylinder 72 as viewed in Fig. 13. Liquid is at the same time exhausted from the forward or right hand end of the cylinder 72 through the connection 264, port 272 and an exhaust connection 278 to a check valve 280 which is connected to the exhaust line 112. When the cross feed reversing and shut-off valve member is turned in a clockwise direction as viewed in Fig. 13, to the feed-out position indicated at 276, liquid flows from the metering valve 210 through the port 270 and connection 264 to the right hand or forward end of the cross feed cylinder 72, while liquid is simultaneously exhausted from the other end through connection 262, port 272, exhaust connection 278, and check valve 280 to the exhaust line 112 as above set forth.

The valve member 268 also has an intermediate or shut-off position designated on the control panel of the machine as a "hand" feed position in which the valve member takes the dotted line position indicated at 274 in Fig. 13, so that the metering valve connections are entirely shut off. The connections 262 and 264 and also the exhaust line 278 are connected through the port 272 permitting liquid to flow freely from one end to the other of the cross feed cylinder 72 for manual operation of the cross feed. A full supply of liquid is maintained at all times in the cross feed cylinder during manual operation of the cross feed by means of a check valve 282 which is connected in parallel with the cross feed relief valve 280 in the exhaust line 278, and operates to permit liquid to be drawn from the exhaust line 112 into the cross feed cylinder as needed.

In order to prevent possible overtravel of the saddle 30 and also to maintain the saddle firmly in each successive position to which it is shifted by the operation of the metering valve 210 above described, the check valve 280 in the exhaust line 278 is spring-loaded by means of a compression spring 284 to provide a relatively high back pressure which is preferably set at 10 lbs. per square inch. With this construction and arrangement of the exhaust connections from the cross feed cylinder 72, it will be readily seen that a relatively high back pressure will be applied against movement of the saddle during hydraulic operation in either direction without in any way interfering with the transfer of liquid from one end of the cylinder to the other for the hand position of the cross feed reversing valve member 268 for manual operation of the cross feed.

In accordance with another feature of the present invention, a control means is provided in the hydraulic connections including the metering valve 210 and the cross feed cylinder 72 which may be adjusted to cause an increment of feeding movement to be imparted to the saddle 30 as above described, at each end of the table reciprocation, or at one end or the other only, or to render said connections wholly inoperative to actuate the cross feed. To this end a control

valve comprising a rotatable valve member 290 is provided in the pipe connection 268 through which liquid passes from the left hand end of the metering valve 210 (see Fig. 13) to the cross feed cylinder 72, and a similar control valve comprising a rotatable valve member 292 is provided in the pipe connection 258 through which liquid passes from the right hand end of the metering valve. An L-shaped duct 294 in the valve member 290 is arranged for one position of the valve to provide a free passage through the pipe connection 266 to the cross feed cylinder, and for another position of the valve to shut off the connection 266, bypassing the liquid from the metering valve 210 through an exhaust connection 296 to the exhaust line 112. An L-shaped duct 298 in the valve member 292 is similarly arranged for one position of the valve member 292 to provide a connecting passageway in the pipe connection 258 to the cross feed cylinder 72, and for another position of the valve to shut off the connection 258, bypassing the liquid forced from the right hand end of the metering valve 210 as shown in Fig. 13 through an exhaust connection 300 to the exhaust line 112. For convenience of operation, each of the valve members 290 and 292 preferably have stem portions which extend upwardly through the saddle casing, and are provided at their upper ends with manually operable lever arms indicated at 302 and 304 as shown in Figs. 1 and 3 respectively.

With the preferred construction shown, the angular position of the cross feed reversing and shut-off valve member 268 is controlled by means of a hand lever 306 which is rigidly secured to a stem portion of the valve member 268 on the control panel formed on the forward end of the saddle 30. A spring-pressed detent 308 formed in the hub of the handle 306 is arranged for engagement in any one of three recesses corresponding to the "in," "hand" and "out" positions of the hand lever and valve to maintain these parts in adjusted position.

In accordance with one feature of the present invention, an interlock is provided between the cross feed reversing and hand feed control lever 306, and the hand feed connections comprising the feed screw 68 and split nut 70 above referred to, which operates when the hand lever 306 is in its intermediate or hand position corresponding to the shut-off position of the valve member 268 to engage the nut 70 with the screw 68, and upon movement of the hand lever 306 to either its "in" or "out" positions, to disengage the nut from the screw, and thus to render the cross feed hand wheel 66 inoperative. As best shown in Figs. 8 and 12, the split nut 70 is carried on a lever arm 310 which is provided at its lower end with a forked hub 312 for engagement with a pivot shaft 314 carried on the machine base. A compression spring 316 coiled about a supporting plunger 318 fitted at one end into a recess in the lever arm 310, and at its other end into a bore 320 in the base, acts to move the lever arm 310 and nut 70 yielding into engagement with the screw 68. The position of the nut 70 is controlled from the cross feed control lever 306 by means of a rearwardly extending control rod 322 which is connected at its forward end to turn with the valve member 268 and lever 306, and is provided along one side with a flattened portion 324. A block 326 carried on a pin 328 offset from the hub portion of the lever arm 310, is arranged for engagement with the control rod 322, and serves to limit the movement of the lever 310 and nut 70 toward the screw 68 under the pressure of the spring 316. With

the hand lever 306, valve member 268 and control rod 322 in the hand position illustrated in Figs. 8 and 12, the block 326 engages against the flattened portion 324 of the control rod 322, so that 5 the nut 18 is permitted to engage with the screw 68. Movement of the hand lever 306 and control rod 322 in either direction to feed position, causes the block 326 to ride onto the round portion of the rod 322, to move the lever arm 318 and nut 18 out 10 of engagement with the screw 68 against the pressure of the spring 316.

In accordance with another feature of the present invention, there is provided with the present construction, a truing control valve 330 (see Figs. 15 2, 5 and 13) which is arranged to provide a steady 20 flow of liquid under pressure through the reversing valve 260 to the cross feed cylinder 72 to provide a continuous cross feed of the saddle at a predetermined rate for the operation of truing the 25 grinding wheel. As best shown in Figs. 5 and 13 of the drawings, the truing valve 330 comprises a rotatable valve member 332 mounted in an extension 334 of the pressure supply line 92, which is connected to the pipe connection 258. There is 30 provided in the truing valve member 332, a duct 336 having a restricted portion 338 through which liquid under pressure is permitted to pass at a relatively slow rate for the operative or truing 35 position of the valve, to the cross feed reversing valve 260 and cross feed cylinder 72. The position of the truing valve member 332 is controlled by means of a hand lever 340 which is mounted on a stem portion 342 of the truing valve member 332 extending through the control panel of the 35 machine.

With the preferred construction illustrated, an interlocking connection is provided between the truing control lever 340 and the control knob 102 for the table throttle valve 80 which is arranged 40 to prevent the movement of the control lever 340 to truing position while the table throttle valve is open, and also operates to prevent the opening of the table throttle valve after the truing valve control lever 340 has been moved to 45 truing position. As best shown in Fig. 2 of the drawings, there is provided on the hub of the truing control lever 340, a segmental disk 344 which is arranged for the closed position of the table throttle valve 80 and control knob 102, to 50 mesh with a corresponding cutaway portion 346 in a disk 348 secured to the stem 100 of the table throttle valve member 84. It will readily be seen from an inspection of Fig. 2, that the movement of the truing control lever 340 to the right to truing 55 position, will engage the segmental disk 344 with the cutaway portion 346 of the disk 348 to lock the table throttle valve in off position illustrated in Fig. 2, and similarly a rotational movement of the table throttle control knob 102 60 will operate to move the cutaway portion 346 out of alignment with the segmental disk 344 to lock the truing control lever 340 in its neutral or inoperative position shown in Fig. 2.

It will be understood that the invention is not 65 limited to the specific embodiment shown, and that various deviations may be made therefrom without departing from the spirit and scope of the appended claims.

What is claimed is:—

70 1. A grinding machine having in combination with a base, a rotary grinding wheel spindle, a longitudinally reciprocable work table, a traversable slide on which one of said elements is carried, a hydraulic system for the machine including a cylinder and piston operatively connected

to reciprocate the table, a reversing valve operatively connected to reverse the direction of movement of the table, a fluid motor operatively connected to traverse the slide, a metering valve operatively connected to admit measured amounts of fluid under pressure to the slide fluid motor to move the slide a predetermined distance, and fluid pressure connections actuated directly by movement of the reversing valve for actuating the metering valve to impart an increment 10 of movement to the slide.

2. A grinding machine comprising with a base, a rotary grinding wheel spindle, a longitudinally reciprocable work table, a transversely movable slide support for one of said elements, a fluid pressure system including a piston and cylinder operatively connected to reciprocate said table, a reversing valve to change the direction of movement of said table, means including a piston and cylinder operatively connected to 15 traverse said slide, a metering valve operatively connected to force a measured quantity of fluid to said second cylinder and cause a predetermined traversing movement of the slide, a pilot valve, and fluid pressure and exhaust connections 20 therefrom for operating the table reversing valve, said connections being constructed and arranged for directing the exhausting fluid to 25 actuate the metering valve.

3. A grinding machine comprising with a 30 base, a rotary grinding wheel spindle, a longitudinally reciprocable work table, a transversely movable slide support for one of said elements, a fluid pressure system including a piston and cylinder operatively connected to reciprocate said 35 table, a reversing valve arranged to change the direction of movement of said table, a fluid motor connected to traverse said slide, a metering valve comprising a cylinder, a piston freely movable therein, a slide control valve having connections 40 to opposite ends of said metering valve operable to discharge a predetermined volume of fluid alternatively from opposite ends of said metering valve to drive the motor, and a pilot valve having pressure and exhaust connections 45 therefrom for operating the table reversing valve, said connections being constructed and arranged for directing the exhausting fluid to 50 actuate the slide control valve.

4. A grinding machine comprising with a base, 55 a rotary grinding wheel spindle, a longitudinally reciprocable work table, a transversely movable slide support for one of said elements, a fluid pressure system including a piston and a cylinder operatively connected to traverse said slide, a metering valve in said system which is operatively connected to force a measured amount of fluid to said cylinder to move the slide through a predetermined distance, and a cross feed control valve including a control element having 60 alternative feed positions to determine the direction of said movements imparted to the slide, and a third hand feed position in which liquid is permitted to circulate freely to and from both 65 ends of the cylinder, mechanical hand feed connections for said slide, and an interlocking device rendered operative by movement of said control element to a feed position to positively disengage said connections.

5. A grinding machine comprising with a base, 70 a rotary grinding wheel spindle, a longitudinally reciprocable work table, a transversely movable slide support for one of said elements, a fluid pressure system including a piston and a cylin- 75

der operatively connected to traverse said slide, a metering valve in said system which is operatively connected to force a measured amount of fluid to said cylinder to move the slide through a predetermined distance, and a cross feed control valve having alternative feed positions to determine the direction of said movements imparted to the slide, a third hand feed position in which liquid is by-passed freely from one end 10 of the cylinder to the other, mechanical hand feed connections for said slide, means for disconnecting said hand feed connections from the slide, and an interlocking device rendered operative by movement of said control valve to a feed position to positively disengage said connections.

6. A grinding machine comprising with a base, a rotary grinding wheel spindle, a longitudinally reciprocable work table, a transversely movable slide support for one of said elements, a fluid pressure system including a piston and a cylinder operatively connected to traverse said slide, a cross feed control valve having alternative feed positions to admit fluid under pressure to one end or the other of said cylinder, and a hand feed position in which liquid is by-passed freely from one end of said cylinder to the other, hand feed connections for said slide including a screw and a cooperating split nut, and a connection from said control valve rendered operative by movement of said control valve to either of said feed positions to disengage the nut from the screw.

7. A grinding machine comprising with a base, a rotary grinding wheel spindle, a longitudinally reciprocable work table, a transversely movable slide support for one of said elements, a fluid pressure system including a piston and a cylinder operatively connected to traverse said slide, a cross feed control valve having alternative feed positions to admit fluid under pressure to one end or the other of said cylinder, and a hand feed position in which liquid is by-passed freely from one end of said cylinder to the other, hand feed connections for said slide including a screw on the slide, a split nut on the base, spring means tending to move the nut into engagement with the screw, and a cam operatively connected to said control valve, actuated by movement of said control valve to either of said positions to disengage the nut from the screw.

8. A grinding machine having in combination with a base, a rotary grinding wheel, a reciprocable work table, a fluid pressure system including a cylinder and a piston operatively connected to move the table, a reversing valve to change the direction of movement imparted to the table by said cylinder and piston, means for supplying fluid to said reversing valve and cylinder at a relatively high pressure, means for exhausting fluid from said cylinder and reversing valve against a relatively low pressure, a table stop valve connected between the reversing valve and cylinder, and arranged for the stop position of said stop valve to connect both sides of said cylinder directly to the pressure supply and exhaust means.

9. A grinding machine having in combination with a base, a rotary grinding wheel, a reciprocable work table, a fluid pressure system including a cylinder and a piston operatively connected to move the table, a reversing valve to change the direction of movement imparted to the table by said cylinder and piston, a conduit from each end of the cylinder to the reversing valve, means for supplying fluid to said reversing valve at a relatively high pressure, means for exhausting

fluid from said reversing valve against a relatively low pressure, and a table stop valve arranged for one position of said stop valve to provide a free passage for liquid through said conduits, and for an alternative position of said stop valve to provide a by-pass between said conduits to both ends of the cylinder and to said pressure supply and exhaust means.

10. A grinding machine having, in combination with a base, a rotary grinding wheel spindle, a longitudinally reciprocable work table, a traversable slide on which one of said elements is carried, a hydraulic system for the machine including a supply line through which liquid under pressure is supplied, a cooperating cylinder and piston for reciprocating the table, a table reversing valve, table hand feed connections including an element shiftable to disconnect the hand feed connections, a hydraulic pressure connection from said supply line acting on said element to disconnect the hand feed, a low pressure exhaust line for said system, a master stop valve in said system movable to connect said supply line directly to the exhaust line to exhaust the pressure throughout said system and thereby to render said hydraulic connections inoperative to move the table and to maintain said element in disconnected position.

11. A grinding machine having, in combination with a base, a rotary grinding wheel spindle, a longitudinally reciprocable work table, a traversable slide on which one of said elements is carried, a hydraulic system for the machine including a supply line through which liquid under pressure is supplied, a cooperating cylinder and piston for reciprocating the table, a table reversing valve, table hand feed connections including an element shiftable to disconnect the hand feed connections, a detent mechanism for maintaining said element yieldingly in either of its alternate connected and disconnected positions, manually operable means for shifting said element, a hydraulic connection from the supply line acting to maintain said element in disconnected position, a low pressure exhaust line in said system, a master stop valve movable to connect both ends of the table cylinder both to pressure and exhaust and thereby to exhaust the pressure throughout said system.

12. A grinding machine having in combination with a base, a rotary grinding wheel spindle, a longitudinally reciprocable work table, a traversable slide on which one of said elements is carried, a hydraulic system for the machine including a cooperating cylinder and piston for reciprocating the table, a table reversing valve, means for supplying fluid under pressure to said reversing valve and cylinder, a stop valve shiftable to render said fluid under pressure inoperative to move the table, a control member movable to shift said stop valve, spring means acting on said member to shift the stop valve to stop position, a latch to maintain said member and valve controlled thereby in running position and a manually operable member movable in one direction to move said control member and stop valve to running position and in another direction to trip said latch.

13. A grinding machine having in combination with a base, a rotary grinding wheel spindle, a longitudinally reciprocable work table, a traversable slide on which one of said elements is carried, a hydraulic system for the machine including a cooperating cylinder and piston for reciprocating the table, a table reversing valve,

- means for supplying fluid under pressure to said reversing valve and cylinder, a stop valve shiftable to render said fluid under pressure inoperative to move the table, a control member movable to shift said stop valve, spring means acting on said member to shift said stop valve to stop position, a latch to maintain said member and valve controlled thereby in running position, and a manually operable member to trip said latch.
14. A grinding machine having in combination with a base, a rotary grinding wheel spindle, a longitudinally reciprocable work table, a traversable slide on which one of said elements is carried, a hydraulic system for the machine including a cooperating cylinder and piston for reciprocating the table, a table reversing valve, means for supplying fluid under pressure to said reversing valve and cylinder, a stop valve shiftable to render said fluid under pressure inoperative to move the table, a control member movable to shift said stop valve, spring means acting on said member to shift the stop valve to stop position, a latch to maintain said member and valve controlled thereby in running position, and connections actuated by movement of the slide to trip said latch.
15. A grinding machine having in combination with a base, a rotary grinding wheel spindle, a longitudinally reciprocable work table, a traversable slide on which one of said elements is carried, a hydraulic system for the machine including a cooperating cylinder and piston for reciprocating the table, a table reversing valve, means for supplying fluid under pressure to said reversing valve and cylinder, a stop valve shiftable to render said fluid under pressure inoperative to move the table, a control member movable to shift said stop valve, spring means acting on said member to shift the stop valve to stop position, a latch to maintain said member and valve controlled thereby in running position, a manually operable member to trip said latch, and connections actuated by movement of the slide to trip said latch.
16. A grinding machine having in combination with a base, a rotary grinding wheel spindle, a longitudinally reciprocable work table, a traversable slide on which one of said elements is carried, a hydraulic system for the machine including a cooperating cylinder and piston for reciprocating the table, a table reversing valve, a second cylinder and piston for moving the slide, a supply line through which fluid under pressure is supplied to said system, an exhaust line for said system, a master stop valve for the machine arranged when moved to stop position to connect the supply line directly to exhaust and thereby to render said hydraulic connections inoperative to move the table and slide, and connections actuated by movement of the slide to a predetermined position to move said master valve to stop position.
17. A grinding machine having in combination with a base, a rotary grinding wheel spindle, a longitudinally reciprocable work table, a traversable slide on which one of said elements is carried, a hydraulic system for the machine including a cylinder and piston operatively connected to reciprocate the table, a reversing valve operatively connected to reverse the direction of movement of the table, a second cylinder and piston
- operatively connected to traverse said slide, a slide reversing valve, a metering valve comprising a cylinder and piston freely movable therein, and having connections from each end thereof to said slide reversing valve, a slide control valve rendered operative upon reversal of the table in one direction to discharge a predetermined volume of fluid from said metering valve through one of said connections, and upon reversal of the table in the other direction to discharge a predetermined volume of fluid from the metering valve through the other of said connections.
18. A grinding machine having in combination with a base, a rotary grinding wheel spindle, a longitudinally reciprocable work table, a traversable slide on which one of said elements is carried, a hydraulic system for the machine including a cylinder and piston operatively connected to reciprocate the table, a reversing valve operatively connected to reverse the direction of movement of the table, a second cylinder and piston operatively connected to traverse said slide, a slide reversing valve, a metering valve comprising a cylinder and piston freely movable therein, and having connections from each end thereof to said slide reversing valve, a slide control valve rendered operative upon reversal of the table in one direction to discharge a predetermined volume of fluid from said metering valve through one of said connections, and upon reversal of the table in the other direction to discharge a predetermined volume of fluid from the metering valve through the other of said connections, and a valve device adjustable to shut off either one or both of said connections from the reversing valve and slide cylinder.
19. A grinding machine having, in combination with a base, a rotary grinding wheel spindle, a longitudinally reciprocable table, a traversable slide on which one of said elements is carried, a fluid motor and connections thereto including a throttle valve having inoperative and adjustable running positions for driving the table, a second fluid motor and connections thereto for moving the slide, a truing control for admitting fluid to move the slide at a truing rate comprising a valve having alternative truing and inoperative positions, and an interlocking device operable when one of said valves is in running position to lock the other of said valves in inoperative position.
20. A grinding machine having, in combination with a base, a rotary grinding wheel spindle, a longitudinally reciprocable table, a traversable slide on which one of said elements is carried, a fluid motor and connections thereto including a throttle valve having inoperative and adjustable running positions for driving the table, a second fluid motor and connections thereto for moving the slide, a truing control for continuously admitting fluid to move the slide at a truing rate comprising a valve having alternative truing and inoperative positions, manually rotatable control elements associated with each of said valves, and an interlocking device comprising cam elements associated with each of said control elements constructed and arranged to lock either of said control members in inoperative position when the other of said control elements is in running position.

GEORGE F. MAGLOTT.
